[57] CLAIM

The ornamental design for a cosmetic pencil sharpener, as shown and described.

DESCRIPTION

FIG. 1 is a perspective view of the cosmetic pencil sharpener showing my new design;

FIG. 2 is a right side elevational view, the left side being a mirror image thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a perspective view with the lid member in an open position, the pencil depicted by means of broken lines being shown for illustrative purposes only and forming no part of the claimed design.
